INJECTOR

Lutwin C. Rotter, Maplewood, Mo., assignor to Lincoln Engineering Company, St. Louis, Mo., a corporation of Missouri

Application November 10, 1951, Serial No. 255,863

4 Claims. (Cl. 103—2)

This invention relates to injectors, and more particularly to lubricant injectors.

This application is related to the two co-assigned, copending applications of Victor G. Klein and Carl H. Mueller, both entitled Injector, Serial No. 240,382, filed August 4, 1951, and Serial No. 255,828, filed November 10, 1951.

Among the several objects of the invention may be noted the provision of an injector, and particularly a lubricant injector of the same general type as that disclosed in the aforesaid copending applications for delivering measured charges of lubricant individually to a plurality of lubrication points upon a single cycle of operation, of improved construction making possible the delivery of smaller individual charges of lubricant than possible with the injectors disclosed in the said copending applications. Other objects will be in part apparent and in part pointed out hereinafter.

The invention accordingly comprises the elements and combinations of elements, features of construction, and arrangements of parts which will be exemplified in the structures hereinafter described, and the scope of which will be indicated in the following claims.

In the accompanying drawing, in which one of various possible embodiments of the invention is illustrated,

Fig. 1 is a plan view of an injector of this invention; Fig. 2 is a longitudinal section taken on line 2—2 of Fig. 1;

Fig. 3 is a longitudinal section taken on line 3—3 of Fig. 2, illustrating a plunger of the injector in a different position from that shown in Fig. 2;

Fig. 4 is an enlarged transverse cross section taken on line 4—4 of Fig. 2;

Fig. 5 is an enlarged detail of Fig. 3;

Fig. 6 is an elevation of a check valve per se of the injector; and,

Fig. 7 is a section taken on line 7—7 of Fig. 6.

Similar reference characters indicate corresponding parts throughout the several views of the drawing.

Referring to the drawing, an injector constructed in accordance with this invention is shown to comprise a cylinder 1. A plunger 3 is movable in the cylinder. An extension 5 of reduced cross section extends from the working end 7 of the plunger (its right end as viewed in the drawing) through an opening 9 in the corresponding end of the cylinder. The cylinder has a lateral inlet port 11 spaced from its right end, and a series of ten longitudinally spaced outlet ports 13, 15, 17, 19, 21, 23, 25, 27, 29 and 31 between the left end of the cylinder and the inlet port. The plunger 3 has a lateral port 33 spaced from its working end 7, and a longitudinal passage 35 for establishing communication to the lateral port 33 from the space 37 in the cylinder around the extension 5. The passage 35 in the plunger is longer than the longitudinal distance from the inlet port 11 to the outlet port 13 nearest the left end of the cylinder. In the passage 35 is a check valve 39 which is adapted to open upon movement of the plunger toward the right end of the cylinder. The plunger is movable from the charging position illustrated in Fig. 2, wherein its working end 7 is retracted past the inlet port 11, toward the right end of the cylinder through a pressure stroke successively to force out individual charges through the outlet ports 13—31, as the lateral port 33 passes the outlet ports.

More particularly, the cylinder 1 comprises an elongate cylinder block of generally square cross section, thereby having four flat sides 41, 43, 45 and 47, and hav-

2

ing a central longitudinal bore 49 with a counterbore 51 at the left end of the bore. At its right end the cylinder 1 has a cylindrical projection 53 of reduced cross section as regards the main body of the cylinder. Threaded on this extension is a cap 55 having the opening 9 therein. Packing 57 is contained in the cap between the head portion of the cap and the end of the projection 53, the plunger extension 5 having a slidable sealing fit in the packing.

Threaded in the counterbore 51 at the left end of the cylinder is a sleeve 59 having an inturned flange 61 at its outer end. The inner end of this sleeve holds in place plunger packing 63. The plunger, toward its left end, extends into the sleeve. Adjacent its left end the plunger has a collar 65. A compression spring 67 acts against this collar to bias the plunger toward the left as illustrated in the drawing. The left end of the plunger and the spring are received in a socket 69 at the inner end of a plunger-operating rod 71. This rod extends out through the outer end of the sleeve and has a shoulder 73 engageable with the flange 61 at the outer end of the sleeve for limiting the outward movement of the rod and the plunger, and determining the retracted charging position of the plunger illustrated in Fig. 2. By pushing in on the plunger-operating rod, the plunger may be driven toward the right end of the cylinder against the return bias of the spring.

The inlet port 11 leads laterally into the bore from the side 41 of the cylinder 1. An elbow fitting 75 for connection of a lubricant supply line 77 for supplying lubricant to the injector through the inlet port is secured on the side of the cylinder by screws 79. More particularly, this fitting 75 consists of a block having a right-angled passage therein. The lubricant delivery line 77 is threaded in one leg 81 of the right angled passage. A tube 83 extends from the other leg 85 of the passage into the inlet port through a packing ferrule 87. This ferrule is radially compressed upon the tube. The screws extend through spacers 89 between the block and the side 41 of the cylinder. The cylinder and the inlet fitting 75 have four screw holes located on the corners of a square, so that the fitting may be oriented in any one of four angular positions. The lubricant supply line 77, for example, may lead to the injector from an elevated oil reservoir for gravity feed of oil to the injector.

The plunger 3 has a close sliding fit in the bore 49. The lateral port 33 in the plunger is formed as an annular peripheral groove with radial openings 91 between the groove and the passage 35 in the plunger. The passage 35 in the plunger is formed by boring the plunger and then counterboring to form a valve chamber 93 with a shoulder 95 at its inner end. As illustrated, the plunger per se is of somewhat reduced cross section at its right end, as indicated at 97. The working end 7 of the plunger is taken as at the inner end of the reduced cross section end portion of the plunger.

The check valve 39, illustrated per se in Figs. 6 and 7, consists of a one-piece molded body, of rubber or the like, and preferably an oil and grease resistant synthetic rubber such as Hycar, a butadiene copolymer with acrylonitrile, having a flat base 99 with a nipple 101 projecting from one face of the base toward the left as viewed in Figs. 2 and 3. The valve is formed with a conical opening or passage 103 into the nipple, the latter being transversely slit as indicated at 105 where it joins the base over part of its periphery, to provide a port through the nipple from the opening or passage 103. As herein illustrated, the base of the valve is in the form of a disc of such diameter as to fit in the valve chamber 93 at the right end of the plunger against the shoulder 95, with the nipple 101 extending into the longitudinal passage 35 in the plunger. The valve is held in the valve chamber by means of a tubular fitting 107 threaded in the valve chamber. This tubular fitting has radial ports 109 which provide for communication from the space around the plunger extension 5 to the interior of the fitting and thence through the valve when the latter is open, to the longitudinal passage 35 in the plunger. At its outer end, the fitting 107 is formed with an enlarged socket 111, receiving a reduced end portion 113 of the plunger extension 5. This reduced end por-

tion of the extension is pinned in this socket by means of a rolled sheet metal pin 115.

The successive outlet ports 13—31 are successively angularly offset. Four of the outlet ports are located in the side 45 of the cylinder opposite the inlet port, three are located in one of the other sides of the cylinder, and the remaining three are located in the remaining side of the cylinder. Apart from the inlet port, the side 41 of the cylinder is completely enclosed. As shown herein, the four outlet ports 13, 19, 25 and 31 lead laterally out of the bore 49 to the side 45 of the cylinder. The three outlet ports 15, 21 and 27 lead laterally out of the bore to the side 43 of the cylinder. The three outlet ports 17, 23 and 29 lead laterally out of the bore to the side 47 of the cylinder. Each outlet port is counterbored at its outer end to form a socket for receiving the end of a lubricant delivery line. The sockets are all designated by the reference character 117, and the delivery lines (tubes) are all designated by the reference character 119. The lubricant delivery lines extend through individual ferrules 121 and through openings in follower plates 123 secured to the respective sides of the cylinder by screws 125 and effecting a radial compression of the ferrules upon the delivery lines in order to hold them secured to the cylinder and to pack them against leakage.

When the plunger is in the Fig. 2 charging position, lubricant flows from the inlet port 11 directly into the space 37 in the cylinder around the plunger extension 5. The lateral plunger port or groove 33 is blocked. The relation of the longitudinal spacing of the successive outlet ports 13—31 and of the last outlet port 31 and the inlet port 11 to the width of the groove 33 is such that as the plunger is moved from its charging position to the right (compare Figs. 2 and 3) through a pressure stroke, the groove 33 comes into communication with the first outlet port 13 as the end 7 of the plunger blocks off the inlet port 11, and then comes into communication with each successive outlet port as it passes out of communication with the preceding outlet port. This is accomplished by making the intervals between the successive outlet ports equal to the width of the groove 33. By "interval" is meant the distance in the longitudinal direction from the trailing edge of any port (its right edge nearest the right end of the cylinder) to the leading edge (the left edge farthest from the right end of the cylinder) of the next successive port. The distance from the working end 7 of the plunger to the right edge of the groove 33 is made equal to the distance from the right edge of the inlet port 11 to the left edge of the first outlet port 13 so that the groove 33 comes into communication with the first outlet port 13 as the plunger reaches a position where it blocks off the inlet port 11.

When the plunger is driven to the right from its charging position illustrated in Fig. 2, lubricant is displaced from within the space 37 in the cylinder around the extension 5 outward through the inlet port 11 until the plunger reaches a position wherein it blocks off the inlet port and wherein the right edge of the groove 33 first encounters the left edge of the first outlet port 13. Then, as the groove passes by the outlet port, the check valve 39 opens and a charge of lubricant is forced out from the cylinder through the passage 35, the radial ports 91, the groove 33 and the outlet port 13 in an amount determined by the displacement of the plunger as it moves through the complete distance over which the groove is open to the port. It will be seen that this distance is equivalent to twice the width of the groove plus the width (diameter) of the port 13. It will also be seen that the displacement, and accordingly the amount of lubricant forced out through the outlet port, will be equal to the product of this distance and the cross-sectional area of the annular space within the cylinder around the plunger extension. Accordingly, the amount of lubricant discharged is much less than it would be in the absence of the extension.

As the plunger continues its pressure stroke, the right edge of the groove 33 next encounters the left edge of the next outlet port 15, as the left edge of the groove is cut off from the preceding port 13. Then, as the groove passes by the port 15, a charge of lubricant is forced out of the cylinder through this outlet port in amount the same as was discharged through the preceding port. This action is repeated as the groove 33 passes by the

remaining outlet ports. Thus, as the plunger is driven through a pressure stroke from its charging position illustrated in Fig. 2, equal and small charges are forced out of the cylinder successively through the outlet ports one after another. Upon return of the plunger to charging position by the spring 67, the cylinder is recharged with lubricant for the next cycle of operation.

Plunger 3 may be operated manually, mechanically or electrically, as may be desired. Mechanical operation may include actuation by various mechanical movements or by fluid pressure means. As herein illustrated, it is contemplated that the plunger will be manually operated, the plunger-operating rod 71, for example, having a knob (not shown) on its outer end for this purpose.

10 The plunger is automatically returned to charging position upon release of the plunger-operating knob by the spring 67. The plunger might also be operated by the special cycling mechanism disclosed in the aforesaid co-pending application Serial No. 240,382, adapted during 15 a single cycle of operation to move the plunger through a full pressure stroke and return stroke, and then to move the plunger through a partial pressure stroke and return, in case it is desired to deliver more lubricant to some points than to others upon each cycle of operation.

20 25 While the specific embodiment of the invention illustrated herein has ten outlet ports, it will be understood that the injector may be constructed with a greater or lesser number of outlet ports as desired. It will also be understood that the principles of the invention may be adaptable to injectors for purposes other than lubrication.

30 In view of the above, it will be seen that the several objects of the invention are achieved and other advantageous results attained.

35 As many changes could be made in the above constructions without departing from the scope of the invention, it is intended that all matter contained in the above description or shown in the accompanying drawing shall be interpreted as illustrative and not in a limiting sense.

I claim:

40 1. An injector comprising a cylinder, a plunger movable in the cylinder toward and away from one end of the cylinder constituting its forward end, the plunger having an extension of reduced cross section extending from its forward end through an opening in the forward end of the cylinder and slidably in sealed relation in the opening, the cylinder having a lateral inlet port and a series of longitudinally spaced lateral outlet ports, the plunger having a lateral port spaced from its forward end and a longitudinal passage for communication from 45 the space in the cylinder around the extension between the forward end of the plunger and the forward end of the cylinder to the lateral plunger port, the intervals between the successive outlet ports of the series being equal to the width of the lateral plunger port, the plunger having a rearward charging position wherein it unblocks the inlet port for flow into the space in the cylinder around the extension between the forward end of the plunger and the forward end of the cylinder, and being movable forward from charging position toward the forward end of the cylinder to block the inlet port as the plunger port comes into communication with the first outlet port of the series and then successively to force out individual charges through the outlet ports as the lateral plunger port passes the outlet ports.

55 60 65 2. An injector comprising a cylinder, a plunger movable in the cylinder toward and away from one end of the cylinder constituting its forward end, the plunger having an extension of reduced cross section extending from its forward end through an opening in the forward end of the cylinder and slidably in sealed relation in the opening, the cylinder having a lateral inlet port spaced from its forward end and a series of longitudinally spaced lateral outlet ports between its other end and the inlet port, the plunger having a lateral port spaced from its forward end and a longitudinal passage for communication from 70 the space in the cylinder around the extension between the forward end of the plunger and the forward end of the cylinder to the lateral plunger port, the intervals between the successive outlet ports of the series being equal to the width of the lateral plunger port, the distance from the forward end of the plunger to the forward edge portion of the lateral plunger port being equal to the distance from the forward edge portion of the inlet port to the rearward edge portion of the first outlet port.

end of the plunger adapted to open upon movement of the plunger toward the forward end of the cylinder, the plunger having a charging position wherein its forward end is retracted past the inlet port for flow into the space in the cylinder around the extension between the forward end of the plunger and the forward end of the cylinder, and being movable forward from charging position toward the forward end of the cylinder to block the inlet port at the instant that the plunger port comes into communication with the first outlet port of the series and then successively to force out individual charges through the outlet ports as the lateral plunger port passes the outlet ports.

3. An injector as set forth in claim 2 wherein the rearward end of the extension is secured to a tubular fitting secured to the plunger at its forward end, the fitting having at least one radial port for communication from the space in the cylinder around the extension to the passage in the plunger.

4. An injector as set forth in claim 3 wherein the fitting holds the check valve in the plunger.
